Patented July 24, 1888.

UNITED STATES PATENT OFFICE.

LEMUEL A. CHICHESTER, OF PHœNICIA, ASSIGNOR TO HEYWOOD BROS. & CO., OF NEW YORK, N. Y.

DESIGN FOR A CHAIR-BACK.

SPECIFICATION forming part of Design No. 18,476, dated July 24, 1888.

Application filed April 21, 1888. Serial No. 271,469. Term of patent 14 years.

To all whom it may concern:

Be it known that I, LEMUEL A. CHICHESTER, a citizen of the United States, residing at Phœnicia, in the county of Ulster and State of New York, have invented and produced a new and original Design for Chair-Backs, of which the following is a specification.

The accompanying photograph is a perspective view of a chair embodying my new and original design.

The leading features of my design consist in the two upwardly-extending back posts, A A; the curved top piece, B, the under side of which is formed with the two scallops b b, one at each end thereof; the cross-piece C, formed with the downwardly-projecting curved end portions, c c, directly underneath and a short distance below the scallops b b; the cross-piece D near the seat of the chair, similar in contour to the cross-piece C, but having the under side of its central portion suitably ornamented with the series of small scallops d; the

series of straight vertical slats E near the center of the back, between the cross pieces C and D, and the series of short ornamental posts F directly over the slats and between the cross-piece C and the top piece, B. The back posts and top piece are ornamented with a series of fillets, G, extending continuously around the back of the chair above the seat. 30

What I claim as new, and desire to secure by Letters Patent, is—

The design for a chair-back herein shown and described, the same comprising the two upright back posts, A A, the horizontal curved top piece, B, the horizontal cross-piece C, the horizontal cross piece D, the vertical slats E, and the vertical posts F, substantially as set forth.

LEMUEL A. CHICHESTER.
